DESIGN FOR A RADIO CABINET

Homer G. Boyle, Cincinnati, Ohio, assignor to
The Crosley Corporation, Cincinnati, Ohio, a
corporation of Ohio

Application January 16, 1939, Serial No. 82,371

Term of patent 7 years

To all whom it may concern:

Be it known that I, Homer G. Boyle, a citizen of the United States and a resident of Cincinnati, in the county of Hamilton and State of Ohio, have invented a new, original, and ornamental Design for a Radio Cabinet, of which the following is a specification, reference being had to the accompanying drawing, forming part hereof.

In the drawing:

Figure 1 is a top plan view of my novel radio cabinet.

Figure 2 is a front elevation of the radio cabinet. Figure 3 is an end elevation, the two ends thereof being similar.

The characteristic feature of my design resides in the tuning section.

I claim:

The ornamental design for a radio cabinet, substantially as shown and described.

HOMER G. BOYLE.
